UNITED STATES PATENT OFFICE.

GEORGE JAMIESON, OF CHICAGO, ILLINOIS.

SAFETY-GUARD AND WORK-HOLDER FOR EDGE-MOLDING MACHINES.

SPECIFICATION forming part of Letters Patent No. 321,728, dated July 7, 1885.

Application filed April 10, 1885. (No model.)

To all whom it may concern:

Be it known that I, GEORGE JAMIESON, a citizen of the United States, residing at Chicago, in the county of Cook and State of Illinois, have invented certain new and useful Improvements in Safety-Guards and Work-Holders for Edge-Molding Machines, (wood-working,) of which the following is a specification.

My invention relates to an attachment that may readily be applied to any wood-working machine of the class above named, which will serve the double purpose of protecting the hands of the workman from contact with the revolving cutters and of holding the work firmly down upon the table, thus enabling the workman to operate more freely and push the work through the machine rapidly, accurately, and with perfect safety.

In the accompanying drawings, Figure 1 is a perspective view of an edge molding and shaping machine with my attachment applied thereto; Fig. 2, a plan view of the preferred form of my invention, upon an enlarged scale, detached from the table, with the cutters shown in dotted lines outside of the ends of a pair of combined safety-guards and spring presser-fingers; Fig. 3, a vertical sectional view in the line *x x* of Fig. 2; and Fig. 4, a perspective view of the adjustable spreader-block, detached, upon an enlarged scale.

The shaping machine consists of a table, A, legs B B', spindle-frame C, vertical spindles D D', of well-known form. The upper ends of the spindles D D' are provided with cutter-heads, by which the cutters are carried, as herein shown. Cutters E are arranged upon cutter-heads comprising upper and lower collars, E' E''. The lower collar, E'', serves to prevent the pattern F from being drawn into the cutters, and the upper collar, E', will prevent the combined safety-guards and spring presser-fingers from being forced against the cutters.

Each combined safety-guard and spring presser-finger consists of a flat or equivalent shaped spring strip or bar, which is arranged horizontally over the table and supported at one end only. The opposite unsupported end of this bar is free and unconnected with any other attachment, and is extended forward to and alongside one of the cutter-heads in position to bear directly upon the work which is held up to the cutter. The under side of the

bar is preferably somewhat rounded or formed with a swell, so as to better adapt it to serve as a presser device.

The combined safety-guards and presser-fingers G are secured to sleeves G', said sleeves being bolted to the under side of a butt-plate, I, by bolts *g g'* in such manner that the combined safety-guards and presser-fingers may be spread and adjusted to any required angle across the table to lie closely against without coming in contact with the upper collars, E', of the revolving spindle, and the butt-plate I may be adjustably secured to the table, as hereinafter described.

The drawings show the combined safety-guards and presser-fingers G arranged between the cutters E E when said cutters are adapted to operate with the wood and patterns between them; but it is obvious that with the form of construction above described the combined safety-guards and presser-fingers may be spread to bear upon the work outside of the cutters, and in either case will serve to hold the work and act as a guard to operate effectively when either cutter is used.

The safety-arms may be vertically adjusted and secured at varying distances above the surface of the table to suit work of any required thickness by means of a standard pin, H, provided with a collar, *h*, and screw-threaded at its lower end, *h'*, to pass through a bored hole in the table A and be firmly held thereon by a nut, H'. The standard pin H passes freely through a hole in the butt-plate I, and a clamping-bolt, I', secures said plate in any desired position upon the pin. A standard pin, K, provided with a collar, *k*', and screw-thread *k'*, is secured to the table by a nut, *k*', and a spreader-plate, L, adjustably secured by set-screw *l* to the pin K, is arranged to press firmly beneath the combined safety-guards and presser-fingers, and serves to hold said arms a suitable distance above the table to be adapted to the thickness of the work, and also serves to hold the combined safety-guards and presser-fingers well braced to exert an elastic pressure upon the work passed beneath them.

Various modifications may be made in my invention as above described without materially departing therefrom, and good results may be obtained from combined safety-guards

and presser-fingers secured independently of each other to the table; but in the form herein described, and illustrated in the accompanying drawings, a single adjustment will answer for both of the combined safety-guards and presser-fingers, as the work is shifted from one cutter to the other to suit the grain of the wood, and an equal adjustment of the combined safety-guards and presser-fingers to secure a uniform pressure upon the work is desirable.

With the above-described attachment an operative is enabled with perfect safety to fearlessly feed and push forward his work beneath the combined safety-guards and presser-fingers to the cutters with great rapidity, and as the pressure of the combined safety-guards and presser-fingers is always uniform, a smooth and perfect finish can be given to the work by unskilled labor.

I claim as my invention and desire to secure by Letters Patent—

1. A safety attachment and work-holder for molding-machines, consisting of a combined safety-guard and spring presser-finger, G, attached at one end to a support and having its opposite end free and extended forward to and alongside of a cutter-head, the free end portion of said combined safety-guard and spring presser-finger being constructed and arranged, substantially in the manner described, to bear directly upon the work at a point adjacent to the cutter-head, and to constitute of itself a safety-guard and work-holding device, substantially as specified.

2. In combination with a molding-machine provided with a pair of cutter-heads arranged above a table, a pair of combined safety-guards and spring presser-fingers, G G, supported at

one end over the table and diverging from their supported ends to their free ends, said free ends being extended alongside of one and the other of the cutter-heads, respectively, and being constructed and arranged, substantially as described, each to bear directly upon the work nearest its allotted cutter-head, in the manner and for the purpose specified.

3. In combination with a molding-machine provided with a pair of cutter-heads arranged above a table, the vertically and horizontally movable combined safety-guards and spring presser-fingers G, each supported at one end substantially as described, and having its opposite end free and extended alongside one of the cutter-heads, substantially in the manner and for the purpose herein specified.

4. The combination, with the table of a shaping-machine, of the diverging arms secured at their contiguous ends to the table and capable of vertical adjustment thereon, and a spreader-plate arranged to be adjustable vertically beneath the said presser-arms, substantially as described, for the purpose specified.

5. In combination with the table and cutter-heads, such as set forth, the butt-plate I, adjustably secured upon a standard pin rising from the table, the spring-arms G, secured in sleeves which are attached to the butt-plate, and a spreader-plate, L, adjustably secured upon a standard pin K, which is susceptible of application to both spring-arms, in the manner and for the purpose herein described.

GEORGE JAMIESON.
